US00D545154S

(12) **United States Design Patent** (10) **Patent No.:** **US D545,154 S**
Lin (45) **Date of Patent:** **** Jun. 26, 2007**

(54) **LEDGE LOCK OF JOINT WRENCH**

7,082,862 B2 * 8/2006 Lee 81/177.8
7,174,815 B1 * 2/2007 Hsieh 81/177.9

(75) Inventor: **Yu-Cheng Lin**, Taichung (TW)

* cited by examiner

(73) Assignee: **Lea Way Hand Tool Corporation**,
Taichung (TW)

Primary Examiner—Raphael Barkai

Assistant Examiner—Randall H. Gholson

(74) *Attorney, Agent, or Firm*—Rosenberg, Klein & Lee

(**) Term: **14 Years**

(57) **CLAIM**

(21) Appl. No.: **29/256,941**

The ornamental design for a ledge lock of joint wrench, as shown and described.

(22) Filed: **Mar. 28, 2006**

DESCRIPTION

(51) **LOC (8) Cl.** **08-05**
(52) **U.S. Cl.** **D8/28**

FIG. 1 is a perspective view of a ledge lock of joint wrench showing my new design;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof;
FIG. 7 is a bottom plan view thereof;
FIG. 8 is a second perspective view of my design, wherein the broken line showing of a lock and key is for illustrative purposes only and forms no part of my claimed design; and,
FIG. 9 is a third perspective view of my design, wherein the broken line showing of a wrench is for illustrative purposes only and forms no part of my claimed design.
